F. H. CRABTREE & A. G. McGREGOR.
MACHINE FOR FASTENING PAPER AND THE LIKE.

APPLICATION FILED JAN. 7, 1908.

961,213.

Patented June 14, 1910.

UNITED STATES PATENT OFFICE.

FREDRICK HERBERT CRABTREE AND ALEXANDER GRANT McGREGOR, OF ANACONDA, MONTANA.

MACHINE FOR FASTENING PAPER AND THE LIKE.

961,213.

Specification of Letters Patent. Patented June 14, 1910.

Application filed January 7, 1908. Serial No. 409,702.

To all whom it may concern:

Be it known that we, FREDRICK HERBERT CRABTREE and ALEXANDER GRANT McGREGOR, citizens of the United States, residing at 5 Anaconda, in the county of Deerlodge, State of Montana, have invented a new and useful Machine for Fastening Paper and the Like, of which the following is a specification.

10 This invention relates to stapling machines and has for its object to provide a strong, durable and thoroughly efficient machine of this character by means of which several sheets of paper or similar material 15 may be securely fastened together and which will be of an inexpensive construction, and in which access may be easily had to the operating parts for repair or renewal of the same.

20 Further objects and advantages will appear in the following description, it being understood that various changes in form, proportions and minor details of construction may be resorted to within the scope of 25 the appended claim.

In the accompanying drawings forming a part of this specification: Figure 1 is a side elevation of a paper stapling machine constructed in accordance with our invention.

30 Fig. 2 is a vertical sectional view of the same. Fig. 3 is a vertical sectional view taken on the line 3—3 of Fig. 1. Fig. 4 is a transverse sectional view taken on the line 4—4 of Fig. 2. Fig. 5 is a detail perspective view of the front end of the staple supporting bar and the anvil. Fig. 6 is a top plan view of a portion of the continuous strip of staples for use in connection with the machine.

35 Similar numerals of reference indicate corresponding parts in all of the figures of the drawings.

The improved machine forming the subject matter of the present invention includes 40 a supporting base 5 provided with laterally extending ears 6 having perforations formed therein for the reception of screws or similar fastening devices 7 by means of which the machine may be secured in position on 45 a table, desk or similar support.

Extending vertically from one end of the base is a tubular member or casing 8 having

its lower end provided with rearwardly extending attaching arms 9 preferably disposed flush with the opposite longitudinal edges of the base and secured to the latter by suitable screws or rivets 10. The forward end of the base is reduced to form an anvil 11, which latter is spaced from the lower end of the casing 8 to form an intermediate chamber adapted to receive the sheets of paper or other material to be fastened together, there being a shoulder 12 disposed at the rear end of the anvil for limiting the inward movement of the sheets of paper when the latter are positioned on the anvil. 55

Slidably mounted in the casing 8 is a reciprocating plunger 13 having its upper end pivotally connected at 14 with the intermediate portion of an operating lever 15. 70 One end of the lever 15 is provided with a handle while the opposite end thereof is pivoted at 16 to a link 17 extending vertically from the base and pivotally mounted at 18 between a pair of spaced lugs 19 extending upwardly from the base and preferably formed integral therewith, as shown.

Secured to or formed integral with the base 5 is a longitudinal bar 20 adapted to support and guide the staples or similar fastening devices employed for uniting the sheets of paper. The staples are preferably in the form of a continuous strip of metal, the individual staples 21 being connected by intermediate webs 22 and provided with 80 depending arms terminating in points 23 adapted to be driven through the paper and clenched on the latter by engagement with the anvil. The forward end of the bar 20 is positioned between and spaced from the 85 attaching arms 9 of the casing so as to permit the strip of staples to be readily fed to the plunger, said bar terminating in a reduced head 24 preferably of the same width as the metal constituting the webs 22. The 90 plunger 13 is provided with a reduced extension 25 which co-acts with the head 24 to cut or sever a single staple from the strip at each downward movement of the plunger. The casing 8 is provided with a vertically disposed slot 26 the side walls of which are extended laterally to form spaced ears 27 between which is pivotally mounted 100 a feeding lever 28 the free end of the latter

being normally and yieldably held in the path of movement of the plunger by a leaf spring 29 which is arranged between the end of the slot 26 and the pivoted end of the lever 28 so as to bear against the outer side of the casing, as shown in Fig. 2, the lower end of the spring being secured to the lever below the pivoted end of the same.

Secured to the free end of the lever 28

10 is a spring pawl 30 having its lower end bifurcated to form spaced arms terminating in angularly disposed lips 31 adapted to successively engage the staples on each side of the connecting webs 22 and automatically

15 feed said staples to the plunger on the upward movement of the latter.

The lips 31 at the end of the pawl 30, as the pawl swings forward, will drop behind the web of the staple in the spaces on opposite sides of the reduced terminal 24, and consequently, positively engage the said web of the foremost fastener and carry it squarely against the casing so that it may be held positively in the path of the plunger and the driving blow will be delivered squarely upon the fastener. On the return movement of the lever, the lips will be slightly bent toward the end of the pawl by the transverse shoulders at the sides of the reduced extension of the head. The reduced construction of the head, furthermore, furnishes ample support for the web of the fastener without projecting under the side arms or fastening legs of the fastener which is to be severed from the strip. Moreover, when the plunger descends there will be no shearing action on any part of the fastener beyond the web and, consequently, there will be no weakening of the fastener as applied to

30 the material secured. On the contrary, a part of the web will be retained on the fastener so as to reinforce that portion of the fastener which receives the clenching blow. Moreover, while the construction provides sufficient support for the fastener it obviates all probability of the plunger being injured by striking a projecting surface near the fastener.

The lower end of the plunger at the reduced extension 25 is provided with a cam face 32 which engages the inner face of the lever 28 and forces said lever rearwardly on its pivot point at each downward movement of the plunger, thereby to permit the lips 31

55 to ride over the fasteners comprising the strip when the plunger is moved to lowered position to sever one of said fasteners from the strip.

As a means for locking the strip against rearward movement during the cutting or severing operation there is provided a locking pawl 33 similar in construction to the pawl 30 and which bears against the staples at the rear of the pawl 30. One end of the

65 spring pawl 33 is secured to a yoke 34 ex-

tending over the bar 20 and having its opposite ends secured to the arms 9 at each side of the bar, as shown. A coiled spring 35 is preferably interposed between the upper end of the casing 8 and a shoulder 36 on the plunger for retracting or elevating said plunger after each downward movement of the lever 15.

In operation the several sheets of paper are introduced in the chamber above the anvil and the lever 15 depressed. As the lever is depressed the plunger 13 will be forced downwardly, the initial downward movement of the plunger thus causing the extension 25 to engage and sever the farthest 70 staple, and a further movement thereof forcing the staple through the paper with the points thereof in contact with the anvil thus bending said points and clenching the same on the bottom of the paper. As the plunger descends the cam face 32 will engage the lever 28 and move the pawl 30 over the face of the strip, the locking pawl 33 serving to prevent rearward movement of the strip during the cutting operation. As the plunger ascends the spring 29 will move the lever 28 carrying the feed pawl 30 in the direction of the head 24 and thus present another staple or fastening device to the plunger for severance from the strip when the plunger is again operated.

While there is illustrated a pivoted lever for actuating the plunger it will be understood that the upper end of the plunger may be provided with a suitable knob or handle for effecting the movement of the plunger without departing from the spirit of the invention.

It will be observed that the parts are compactly arranged and that the feeding lever and the retaining pawl 33 are accessible for cleaning, repairing or renewal without the removal or disarrangement of any of the parts.

Having thus described the invention what is claimed is:

The stapling machine herein described and shown comprising a base plate having an anvil at one end, a tubular casing on the base plate over the anvil provided with a vertical slot in its rear side at its lower end, a guide bar on the base plate extending into the lower end of the casing and having a reduced extremity spaced from the side of the casing, a yoke extending over said guide bar, a spring pawl secured upon said yoke and projecting toward the casing to engage staples supported on the guide bar, a plunger mounted within the casing and provided at its lower end with a reduced extension adapted to sever a staple and drive the same against the anvil, a cam surface being formed on the plunger in rear of and adjacent to the said extension, a feeding lever pivoted on the casing and projecting through

115

130

the slot therein into the path of the plunger, a spring pawl secured to the lower end of the feeding lever to engage the staples, a leaf spring secured to the inner side of the feeding lever and arranged between the same and the end of the slot in the casing, and means for operating the plunger.

5 In testimony that we claim the foregoing

as our own, we have hereto affixed our signatures in the presence of two witnesses.
